UNITED STATES PATENT OFFICE

ALVA F. SPRING, OF CLEVELAND, OHIO, ASSIGNOR TO THE LAKE ERIE CHEMICAL COMPANY, OF CLEVELAND, OHIO, A CORPORATION OF OHIO

HAND GRENADE, ETC.

Application filed July 13, 1931. Serial No. 550,567.

This invention relates to devices for the dispersion of irritating gases, tear gases, disabling gases, fumes, and the like, and more particularly to hand grenades containing chemicals which develop or evolve irritating and disabling gases when "fired". The invention also relates to the sealing of such devices and grenades.

An object of the invention is to provide a means to hermetically seal such devices or grenades, whereby the contents are preserved from deterioration, and leakage of irritating fumes and gases is prevented.

A further object is to provide a destructible seal for such devices, which will be strong enough mechanically to resist accidental destruction, and still be capable of quick destruction and to liberate the gases or fumes when the pressure and temperature in the grenade reaches a desired degree after it has been "fired".

A further object is to provide a metallic seal for grenades, etc., which is not readily corroded by the contents of the device, and which is water-proof, moisture-proof, and permanent.

Hand grenades, or similar devices of this type, are frequently used by the police authorities to disperse mobs, capture criminals, and subdue prison riots, etc., by throwing the grenades into the mob whereupon the grenade "goes off" and large volumes of disabling gases and fumes are liberated. If the grenade does not "go off" promptly, it may be picked up by someone in the mob and thrown back toward the police, and liberate the gases later; but if it is provided with a seal such as described herein, the seal is quickly destroyed and the disabling and irritating gases and fumes are discharged promptly among the mob, with the result that persons in the mob are overcome, or the mob dispersed by said gases and fumes.

Heretofore, grenades of this type have been sealed with insulating electric tape, or similar materials, which materials have not been moisture-proof or water-proof, and have permitted the admission of moisture to the contents of the grenade resulting in the deteri-

oration of the chemicals in the charge, and of leakage of evolved gases.

One advantage of a seal of the type described herein, consisting of a soft low-melting metallic seal, is that the grenade may be hermetically sealed, preventing the deterioration of the charge, and yet the seal is sufficiently soft and fusible that upon firing the grenade the seal will be quickly destroyed and the liberated gases will be promptly discharged, whereas with a high melting point metal seal the gases will not be promptly discharged but will be retained in the grenade for some time, sufficient time for the grenade to be picked up as noted above, and thrown away by the persons it is intended to subdue or capture.

In the accompanying drawing—

Fig. 1 is a longitudinal sectional view of a grenade, with the fuse head in elevation, showing one type of seal;

Fig. 2 is a broken view of a grenade showing a different type of seal;

Fig. 3 are sectional and plan views of a disc or filler of soft fusible metal used in Fig. 1; and

Fig. 4 are side and bottom views of a soft fusible metal band or cover which is used to seal the grenade in Fig. 2.

In Fig. 1, a grenade body 1 is provided with a number of holes, vents, or openings 2 which are sealed by pressing therein seals consisting of discs or fillers 3 (Fig. 3) of a soft fusible metal, such as Wood's metal, Rose metal, soft solder, etc., the seals may have a thickness of from 0.004 to 0.008 inch, or any desired thickness for special services; the edges of the discs or fillers 3 are suitably soldered to the body of the grenade as shown at 4, after which the burr is ground off, showing a smooth wall as at 5 on the right side of Fig. 1. The grenade is then filled with the gas generating chemicals 6, which have been mixed with a suitable explosive, for example, smokeless powder; a starting mixture 7 is then placed upon the chemicals 6, the starting mixture may consist of any of the well-known compositions used for this purpose, for example, smokeless powder and celluloid. After the starting composition 7 has

solidified, the fuse head 8 is screwed into the grenade body, the fuse head being provided with a cotter pin 9 to which is attached the ring by which the pin 9 is withdrawn. The fuse head 8 is provided with a match head 10 which is in close proximity to the starting composition 7.

Fig. 2 resembles Fig. 1, except that the holes 2 are sealed with a sheet of thin metal, for example, a metal band 11, Fig. 4; the band may have a thickness of from 0.004 to 0.008 inch, and is placed as shown at 11a, and then soldered at the edges to the body of the grenade as at 12. The grenade is then filled as described under Fig. 1, and the fuse head 15 attached.

Any of the standard mixtures of chemicals which generate disabling gases may be used. For example, a charge consisting of about 20 seventy percent of smokeless powder, about twenty-seven percent of chloracetophenone, and about three percent of magnesium oxide may be used. Other disabling gas-generating 25 composition may also be used.

When it is desired to use the grenade to 30 subdue a mob, etc., the cotter pin 9 is withdrawn by the ring, which releases a trigger (not shown), and the grenade immediately thrown; the trigger "fires" the fuse and 35 match head 10, igniting the starting mixture 7, which latter "fires" the chemical charge 6, generating considerable heat and pressure, and liberating the disabling gas. The combined heat and pressure will quickly tear off or melt the soft fusible seals 3 in Fig. 1, and 40 11 in Fig. 2, exposing the openings 2 which permit the disabling gas to discharge as jets under pressure, the pressure being sufficient to rapidly distribute and disperse the disabling 45 gas over a relatively large area; at times the jets of gas emerge from the holes 2 under sufficient pressure to bounce or toss the grenade about in a succession of leaps or jumps, thereby more thoroughly distributing the disabling 50 gas and having the effect of striking terror into the mob or riot. The soft fusible metal seals are destroyed too rapidly to permit the grenades to be picked up by any one in the mob and thrown away.

55 In the claims, the term "Wood's metal" is intended to cover also Rose metal, and very low melting temperature solder.

I claim:—

1. A grenade comprising a body portion, 55 perforations in said portion, said perforations metallically sealed by a soft low melting alloy seal of Wood's metal.

2. A grenade comprising a body portion, 60 perforations in said portion, and soft fusible metallic fillers of Wood's metal in said perforations and hermetically sealed by a metallic joint to said body portion.

3. A grenade comprising a body portion, 65 perforations in said portion, said perforations covered by an easily fusible metallic

sheet, said sheet metallically sealed to said portion to provide a hermetically sealed gas-proof, and water-proof metallic joint.

4. A grenade comprising a body portion, 70 perforations in said portion, said perforations covered by a soft fusible metallic band of Wood's metal, said band metallically sealed to said portion to provide a hermetically sealed gas-proof, and water-proof metallic joint. 75

In testimony whereof I hereby affix my signature.
